UNITED STATES PATENT OFFICE.

HENRY J. SIEMS, OF SENECA, KANSAS.

DESIGN FOR A SCHOOL-DESK AND CHAIR-FRAME.

No. 40,091.

Specification for Design.

Patented June 22, 1909.

Application filed December 26, 1908. Serial No. 469,492. Term of patent 3½ years.

To all whom it may concern:

Be it known that I, HENRY J. SIEMS, a citizen of the United States, residing at Seneca, in the county of Nemaha and State of Kansas, have invented a new, original, and ornamental Design for a School-Desk and Chair-Frame, of which the following is a specification, reference being had to the accompanying drawing, forming part thereof.

Figure 1 is a perspective view, and Fig. 2

a side elevation of a frame for a school desk and chair, showing my new design.

I claim:

The ornamental design for a school desk and chair frame, as shown.

HENRY J. SIEMS.
